Louis Jean Girard
ATTORNEY

UNITED STATES PATENT OFFICE.

LOUIS JEAN GIRARD, OF THIONVILLE AT SURESNES, FRANCE.

RELAY.

Application filed November 6, 1925, Serial No. 67,284, and in France December 12, 1924.

The object of this invention is to provide an electro-magnetic relay which will permit the control, either directly or with the aid of an auxiliary electric circuit, of a circuit-breaker releasing mechanism, or the opening and closing of any electric circuit, by utilizing the variation of the intensity of current traversing in the conductor wherein said relay is inserted to operate the same.

10 The action of the relay can be instantaneous or retarded; and in the latter case, it is merely necessary to connect any one of the commonly-used retarders to the relay.

Being adapted to operate with one hundred ampere-turns, the improved relay does away with the serious drawbacks appertaining, on high tension, to generally used relays which offer a great number of ampere-turns (from 800 to 1500) and which, in consequence, involve considerable self-inductance and current consumption.

The characteristic features of operation are as follows:

On a laminated core having the form of 25 an apertured cylinder is wound a coil through which flows the current the intensity of which is desired to be limited. Under action of the magnetic field developed in said core by said current, an armature is drawn into the aperture or air-gap so provided, thereby tilting a lever that controls either the circuit-breaker releasing mechanism or the opening or closing of an interrupter of the auxiliary circuit.

30 Adjustment in accordance with predetermined intensity limits is effected by varying the spacing between the armature and the core.

Retardation of action is obtained by interposing between a fixed point of the core and the end of the lever any suitable retarding device.

Said relay is completed by a short-circuit or overload operated device. Locking is effected by means of a soft-iron pallet attracted by a magnetic leakage field produced in a supplemental passage or gap in the core, said pallet permitting the movable portion of the relay to be locked so as positively to prevent recoupling. Since the leakage field produced by the intensity at which the relay is set to operate is insufficient to attract the soft-iron pallet, and since the movable portion is normally unlocked, recoupling remains possible until said intensity is exceeded.

An embodiment of the invention is illustrated in the accompanying drawing, wherein:

Figure 1 is a view partly in elevation and 60 partly in vertical section;

Figure 2 is a top plan view;

Figure 3 is a bottom plan view;

Figure 4 is a view at right angles to Figure 1; 65

Figure 5 is a sectional view according to line X—Y of Figure 4.

The improved device comprises a laminated sheet iron annular core C (Figure 1) which is open or cut away along its radii 70 a—b and c—d (Figure 5) and surrounded by a winding L, one terminal of which is indicated at A; said device being connected in the electric circuit by means of the part A and of the relay-supporting member B. 75

The winding is connected to the body of the relay at point Z (Fig. 3).

A free annular space is provided between the sheet-iron core and the winding so as to avoid current shunts into the core. 80

An armature D (Figures 1, 2, 4 and 5), also laminated, and having such a diameter and such a form as to close completely the cut away portion or opening a—b—c—d of the core, is carried by a bar F rocking on 85 trunnions or pins E carried by a frame G¹ G² (Figure 4), secured on core C.

H (Figure 1) indicates a series of tapped holes formed in the stationary part or body of the relay and adapted to receive interchangeably a stop pin or the like which is designed to be engaged by the adjacent end of bar F when the latter is in its position of rest, whereby such position can be varied with relation to core C, as well as the space 90 between parts A and C and, hence, the current intensity required for operation.

The bar or lever F carries adjacent its stop-engaging ends two hooks I¹, I² adapted to be connected, one to the control rod of 100 the circuit-breaker releasing mechanism or the operating rod of the auxiliary circuit interrupter, and the other to the end of the retarding device, said device itself being secured at K (Figure 1) to the stationary 105 body.

The locking device is constructed as follows:

On the stationary portion of the relay, at the upper part and on each side of the gap or opening a—b—c—d, are located two bearings L¹, L² (Figures 2 and 4) in which is

journalized a spindle M carrying at one end a fixed arm N provided with a notch O.

On spindle M and at the middle thereof is fixed a second arm P provided with a counter-weight and carrying a spur Q. Said spur is adapted to penetrate into a seat R provided for this purpose in armature D of the relay.

A soft-iron pallet S is secured by means of 10 two screws on a spring blade T which is itself fastened by screws to the stationary portion of the relay. The two-part member thus formed is movable directly in front of an open gap or passage U in the core C 15 (Figure 5) and the arm N extends directly over its upper end.

A stop screw V permits the position of the pallet to be adjusted according to the overload at which the device is to be locked, such 20 adjustment being effected by moving the screw endwise so as to limit the inward movement of the pallet caused by spring T.

The operation is as follows:

1. With the intensity at which the relay 25 is adjusted to be operated, the magnetic field produced in the auxiliary air-gap U is insufficient to attract pallet S, and spur Q remains in inoperative position above seat R, being held against movement by spindle M, which is itself kept stationary by arm N bearing against the upper end of pallet S.

2. When an overload occurs, the leakages into the aforesaid field increase its force to the point where it is sufficient to attract pallet S, whereupon said pallet comes to engage 35 into notch O and releases member N. Spur Q, then influenced by member P and the counter-weight thereof drops into seat R in armature D, thus locking the armature and its bar F and related parts against movement and thereby preventing any subsequent recoupling.

It is to be clearly understood that the device may be utilized as well with alternating 45 as with direct current, and that, the above described embodiment being in no way limitative, the right is reserved to introduce any desirable constructional modifications without being deemed to have departed from 50 the scope of the invention.

Having now particularly ascertained and fully disclosed the nature of my said invention as well as the manner in which the same is to be performed, I declare that what 55 I claim is:

1. An electro-magnetic relay, comprising a stationary body portion; a magnet carried thereby and embodying an annular core provided with a lateral opening, and a winding 60 encircling said core; an armature shaped to fit conformably in the core opening; a lever pivoted intermediate its ends to the stationary body portion of the relay below said core and carrying the armature on one end thereof; and an adjustable stop carried by

said body portion for engagement by the other end of the lever to determine the normal position of the armature with relation to the core.

2. A relay, according to claim 1, in which the stationary body portion includes a member formed with a series of perforations, and in which the stop consists of a pin for interchangeable engagement in said perforations.

3. An electro-magnetic relay, comprising 75 a magnet, an armature therefor, a detent mounted on the magnet for positive engagement with the armature to lock the latter against movement, and an overload-operated trip movable independently of and relatively 80 to the detent and acting normally to hold the same in inoperative position but releasing it automatically when an overload occurs.

4. An electro-magnetic relay, comprising 85 a magnet, an armature therefor, a detent mounted on the magnet for positive engagement with the armature to lock the latter against movement, and an electro-magnetic trip member directly associated with the magnet but normally spaced therefrom 90 so as to hold the detent against operation; said trip member being movable independently of and relatively to said detent and adapted to be drawn toward the magnet when an overload occurs so as to release the detent. 95

5. An electro-magnetic relay, comprising 100 a magnet, an armature therefor provided with a seat, a detent mounted on the magnet and engageable in said seat to lock the armature against movement, and an overload-operated trip movable independently of and relatively 105 to the detent and acting normally to hold the same in inoperative position but releasing it automatically when an overload occurs.

6. An electro-magnetic relay, comprising 110 a magnet, an armature therefor, a spindle mounted on the magnet and provided with a counterweight for rocking it in one direction, a detent connected to the spindle and adapted to engage and lock the armature against movement when said spindle is rocked by its counterweight, and an overload-operated trip movable independently of and relatively to the detent and acting normally to hold the 115 spindle against rocking but automatically releasing it when an overload occurs.

7. An electro-magnetic relay, comprising 120 a magnet, an armature therefor, a spindle mounted on the magnet and provided with a counterweight for rocking it in one direction, a detent connected to the spindle and adapted to engage and lock the armature against movement when said spindle is rocked by its counterweight; an arm on the spindle having a notch in its lower surface; and a trip normally engaging the said lower surface of said arm at one side of the notch to hold said detent and spindle against 125 operation but automatically movable into said 130

notch when an overload occurs, thereby to permit the operation of the detent.

8. An electro-magnetic relay, comprising a magnet having main and auxiliary air gaps, an armature movable into and out of the main gap, a detent on the magnet engageable with the armature to lock the latter against movement, and a trip cooperative with the auxiliary gap and acting to hold the detent normally in inoperative position; said trip being normally spaced from said auxiliary gap but moved automatically toward the same when an overload occurs so as to release the detent.
10. An electro-magnetic relay, comprising a magnet having an air gap, an armature

associated with the magnet, a detent on the magnet engageable with the armature to lock it against movement, and a trip cooperative with said air gap and acting to hold the detent normally in inoperative position; said trip being normally spaced from the gap but moved automatically toward the same when an overload occurs so as to release the detent.

10. An electro-magnetic relay, according to claim 9, in which the trip embodies a spring blade mounted on the body of the relay, and a soft iron member attached to said blade and normally pulled away from the magnet by the action of the blade.

In testimony whereof I affix my signature.

LOUIS JEAN GIRARD.
